SPOON HOLDER

Patrick B. Marchion, Fostoria, Ohio

Application November 9, 1955, Serial No. 38,808

Term of patent 14 years

(Cl. D44—29)

Fig. 1

Fig. 2

Fig. 3

I claim:

The ornamental design for a spoon holder, as shown.
